DECORATIVE TABLE TOP

Beatrice W. Rice, New York, N. Y.

Application December 9, 1943, Serial No. 513,543

4 Claims. (Cl. 211—1)

The present invention relates to table tops, and more particularly to means whereby table tops are rendered decorative as well as functionally useful.

As a feature of the present invention, there is provided a table top having a depressed ornamental design adapted to contain such table decorations as flowers, fruit and the like, so that these table decorations conforming to the pattern of this design, lend esthetic appeal to the table top.

As a further feature, the ornamental table top depression is adapted to contain water, so that flowers arranged in said depression can be kept fresh. Means are provided whereby water can be easily drained from the table top depression, to permit this water to be changed, to permit changeovers to table decorations that do not require water such as fruits, or to permit the use of the table top for ordinary table service.

As another feature, there is provided an insert which conforms in shape with the design of the ornamental depression in the table top, and which is adapted to be set into said depression to fill it. This insert, when set into the depression, has its top surface flush with the upper surface of the table top, so that this table top in conjunction with said insert presents a substantially continuous supporting surface. When the insert is so set in the table top depression, this top can be used for ordinary table service, and may for that purpose be covered with a tablecloth as in the case of the usual table top.

The insert can be arranged to fill the entire table top depression, or these inserts may be in sections, so that only portions of the depression may be filled and blocked off, while the remaining unfilled portions of the depression can be used for receiving such table decorations as flowers or fruits.

Various other features and advantages of the invention will be apparent from the following particular description, and from an inspection of the accompanying drawing, in which:

Fig. 1 is a top plan view of a table top embodying the features of the present invention;

Fig. 2 is a section of the table top taken on line 2—2 of Fig. 1, and showing in conjunction therewith but separated therefrom in side elevation the insert adapted to be set into the ornamental depression of the table top; and

Fig. 3 is a top plan view of the insert.

Referring specifically to the drawing, there is provided a table top 10 in the form of a plate or slab, which is shown of rectangular outline,

but which, as far as certain aspects of the present invention are concerned, may be of any suitable shape, as for example circular or elliptical. Although only the table top 10 is shown, it must be understood that this table top may be supported on legs as in the conventional table. These legs may be secured to the table top 10 to form a permanent unit therewith, or may be of the type which will permit the table top to be lifted and detached from the legs.

The table top 10 may be of any suitable material which will permit the formation of a design depression therein as will be described. For that purpose, the table top 10 may be of glass, plastic or of cast metal such as aluminum.

The upper section of the table top 10 is provided with a centrally disposed depression 11 defining a sunk ornamental design. This design may be of any suitable outline according to the decorative effect desired, and is shown for the purpose of illustration simply as a cross-shaped channel having one section 12 extending lengthwise of the table top and a shorter section 13 intersecting said section 12 and extending across 25 said table top.

The ornamental table top depression 11 may be supplied with water, so that flowers inserted therein may be kept fresh. In order to permit easy removal of this water, there is provided a drain pipe 14 connected at its inlet to the bottom of the depression 11, and having a valve 15 near the edge of the table top easily accessible for convenient manipulation. A receptacle at the discharge end of the pipe 14 can be conveniently held in position to catch the drainage from the cavity 11 when the valve 15 is opened. This pipe 14 would desirably be disposed within the confines of the table top border, so that it would normally be out of view.

In order to assure complete drainage of the depression 11, the bottom walls of said depression are arranged to discharge towards the inlet of the drain pipe 14. For that purpose, the bottom walls 16 and 17 of the channel conformations 45 12 and 13 respectively slant downwardly towards the inlet of the drain pipe 14.

To permit the cruciform cavity or depression 11 to be blocked up when it is desired for instance, to cover the table top 10 with a table cloth, there is provided an insert 20 which is shaped to conform with the shape of said depression, and which, in the specific form shown, is cross-shaped. This insert 20 may be made of the same material as that of the table top 10 or of any suitable decorative material, and

is adapted to be set snugly into the design cavity 11. In this set position, the insert 20 will have its top surface substantially flush with the top surface of the table top, so that this table top in conjunction with said insert 20 will present a continuous uninterrupted flat surface.

The insert 20 is desirably constructed to permit its easy insertion into or removal from the cavity 11. For that purpose, the insert 20 may be provided with a key hole 21 having a circular bore 22, a circular undercut groove 23 of larger diameter at the lower end thereof, and a keyway 24 extending along one side of said bore and down into the groove 23.

A key may be inserted into the keyhole 21 to effect the raising or lowering of the insert 20. This key may consist of a shaft which has a diameter to permit it to extend into the bore 22, and which has a flange on one side adapted to extend into the keyway 24. When the bottom of the key shaft reaches into the bottom of the groove 23, the key may be turned, so that the flange is out of registry with the keyway 24. In this position, the key flange will serve as an abutment on which the insert 20 will rest in the lowering or raising of the insert.

If desired, a simple hole may be provided in the insert 20 to permit the insertion of a finger therein for raising or lowering said insert, or a hinge ring may be provided set in a groove in the insert to permit it when not in use to lie flat with the top surface of said insert.

Although the insert 20 is shown forming a single unit coextensive in size with the cavity 11, as far as certain aspects of the invention are concerned, this insert may be divided into sections, so that instead of filling the whole cavity by a single insert unit, only parts of the cavity may be filled, while the other parts are left vacant for the reception of flowers, fruit or the like. In this manner, any number of ornamental effects can be obtained by the setting of the required insert section in the cavity 11. For example, end pieces inserted in the outer ends of the channel 12 will shorten the vacant part of this channel, so that a cross design somewhat different in proportions to the original depression design is obtained. Also, by having a cruciform insert with arms shorter than the corresponding channels of the table top depression 11, the ends of these channels alone are left vacant, so that flowers inserted in these channel ends will form a pleasing decorative design which can be further enhanced by a bowl, vase or similar decorative piece in the middle of the table top over the cruciform insert 20.

The insert 20 itself may ornamenteally com-

bine with the table top 10 to present in conjunction therewith a pleasing decorative effect, even though said table top may be uncovered. For example, this insert 20 may have some suitable design on it to blend with the design on the rest of the table top, and may be colored, as for example by making it of colored glass, so that this insert contrasts or blends in color with the table top 10. By making this insert 11 appealing in design and/or color, it may be used to decorate the table top 10, when flowers or fruits are not available.

I have described what I believe to be the best embodiment of my invention. I do not wish, however, to be confined to the embodiment shown, but what I desire to cover by Letters Patent is set forth in the appended claims.

I claim:

1. In combination, a table top having a central depression following a predetermined ornamental pattern and adapted to contain table decorations, said depression being adapted to contain water, and having a drain opening at the bottom, means for controlling drain flow from said opening, said depression having its bottom walls slanting downwardly towards said opening, and an insert adapted to be set in said depression to block up at least a portion of said depression, said insert when set in said depression having its upper surface substantially flush with the upper surface of said table top.

2. In combination, a table top having a depression following a predetermined ornamental pattern and adapted to contain table decorations, and an insert adapted to be set in said depression to block up at least a portion of said depression, and having a keyhole adapted to receive a tool by which said insert may be lifted out of said depression.

3. The combination as described in claim 2, in which said keyhole has a circular bore, a circular undercut groove of larger diameter at the lower end thereof, and a keyway extending along one side of said bore and down into said groove.

4. In combination, a table top having a central depression following a predetermined ornamental pattern and adapted to contain table decorations, said depression being adapted to contain water, and having a drain opening at the bottom, means for controlling drain flow from said opening, and an insert adapted to be set in said depression to block up at least a portion of said depression, said insert when set in said depression having its upper surface substantially flush with the upper surface of said table top.
